LINE GUIDE FOR COPYHOLDERS

Harry Van Buren, Carlsbad, N. Mex.

Application July 22, 1943, Serial No. 495,754

3 Claims. (Cl. 120—29)

This invention relates to improvements in line guides for typewriter copy holders, and its objects are as follows:

First, to provide a line guide which is readily attachable and detachable from any known style of copy holder, one of the outstanding features of the line guide being the provision of a magnifying means by which the copyist may not only concentrate upon the given line but through which the line is magnified to sufficient proportions to make it easily read.

Second, to provide the foregoing magnifying means in the form of a tube which is filled with a solution of glycerin and water, a secondary purpose of said tube being to smooth the copy matter and thus prevent the copyist from getting a distorted image of the line of text thereunder.

Other objects and advantages will appear in the following specification, reference being had to the accompanying drawing, in which:

Figure 1 is a front elevation of the improved line guide, showing it applied to a typewriter copy holder.

Figure 2 is a perspective view of one end of the line guide and copy holder.

Figure 3 is an end elevation illustrating the two positions which the line guide may occupy with respect to the copy holder.

As will be seen especially from Fig. 1, the improved line guide is used as a supplement to a known style of typewriter copy holder, its especial purpose being to magnify the lines of text one at a time. Further, it is easily seen that the improved line guide may be furnished with independent mounts of its own, that is to say, it can be used in conjunction with any appropriate copy support without necessarily depending upon the known structural elements of a commercial copy holder.

However, the latter combination is preferred because it enables keeping the line guide down to simple proportions and structure, and enables the copyist to use or not use the magnifying line guide at will. With the latter understanding in mind, attention is directed to the drawing. The panel of a known style of typewriter copy holder is designated 1. The page containing the text to be copied is designated 2. 3 indicates the normal size of the printed or typewritten matter, and 4 is a specimen of the magnified text.

The copy holder here shown includes a stationary blade 5 which operates as the known line guide. This blade is carried by a rectangular frame 6 including the side arms 7. The panel 1 is adapted to be moved up with a stepped motion 55

by mechanism with which the invention has no concern. The invention is attached to the rectangular frame, and is constructed in the following manner:

5 A thin, round tube 8 of optical glass is filled with a solution 9 (Fig. 1) composed of glycerin and water. This solution is sealed in the tube by end caps 10, each of which has a pintle 11 by means of which the tube is supported by the respective arms 12.

Each pintle is inserted in a slot 13 in one end of the respective arm (Fig. 2), where it is held when the base of an oppositely directed slot 14 in a pivoted clip 15 is brought into contact therewith.

15 Each clip is pivoted to the respective arm, and it has a finger-piece 16 by which it is actuated.

The opposite ends of said arms are attached upon a small transverse rod 17 which, in turn, is pivoted through the arms 18 of clamps 19. The other arms of said clamps provide mounts for one end of springs 20, the other end of said springs being attached to the arms 12.

25 Lock nuts 21 are screwed onto the rod 17 at its ends, and each arm 12 is mounted and held firmly on the respective end of the rod between a pair of the lock nuts. The lock nuts are intended to be tight, that is to say, they hold the arms 12 firmly to the rod 17 which is pivoted through holes in the arms 18 of the clamps 19, thus permitting the line guide to be swung either up (full lines Fig. 3) or down (dotted lines), depending on whether or not the copyist has an immediate need for magnifying the line of text. The spring 20 holds the magnifying line guide against the page 2 in either of the two positions.

30 Each foregoing clamp 19 is affixed to a side arm 1 by a screw 22 which is inserted through an inner plate 23 where it has a wing nut 24. This plate is flanged at 25, and the flange is intended to engage on the top edge of the arms and so prevent turning.

The magnifying tube 8, with the proper proportions of glycerin and water will pick up and show the image of one line only of typewritten text or other printed matter, as illustrated at 4 (Fig. 1). The degree of magnification may be increased or decreased by varying the proportions of glycerin and water. Thus the line guide is adjustable, so to speak, to different eye-sights.

35 50 The operation is readily understood. It has been pointed out that when the magnifying tube 8 is lowered (dotted lines, Fig. 3) it is temporarily out of the copyist's way. The intended use of the line guide is depicted in Fig. 1, where the magnifying means not only singles out the line of

text so that the copyist may concentrate his or her attention thereupon, but it also enlarges the line so that the work can be done with the least mental fatigue. Inasmuch as the tube 8 is held under the tension of the springs 20 said tube affords the additional advantage of smoothing the paper so that the magnified image 4 will not be distorted.

As the copy holder is operated to raise the page 2 step-by-step, the friction of the copy against the tube 8 causes said tube to revolve slowly. This avoids any appreciable wear of the tube which might occur were the latter stationary. Another feature which must not be overlooked is the provision of clips 15 for instantly removing the tube 8. It is intended that the copyist shall be supplied with several diameter sizes of tubes, and with tubes of different degrees of magnification. In order to secure the proper vision of the image of the line magnified by the tube, the copyist merely inserts the proper tube and raises and lowers the copy holders to the proper place. The virtue of a larger tube than the one shown is that more than one line may be picked up at a time.

I claim:

1. A line guide comprising magnifying means for producing an enlarged image of at least one line of text, clamps to be affixed to the supporting means of the line finder of a copy holder, arms carrying the magnifying means and being pivotally connected to the clamps so that the arms and magnifying means can swing, and

springs connected at their ends with the respective arms and clamps holding the magnifying means under tension against the page containing the text.

5. A line guide comprising magnifying means for producing an enlarged image of at least one line of text, clamps which are detachably secured to the supporting means of the line finder of a copy holder, a pair of arms, each having 10 means to which the magnifying means is detachably connected in a working position, means by which said arms are movably mounted on the clamps so that said arms and magnifying means can swing, and springs connected at their ends to the respective arms and clamps holding the magnifying means under tension against a page on the copy holder containing the text.

15. A line guide comprising magnifying means which consists of cylindrical paper pressing means, end caps for the pressing means, each of 20 said caps having a pintle, arms to one end of each of which the respective caps are attached, there being clips on the arms to catch and hold the pintles, clamps to be secured to supporting means in reference to a page of text to be copied, a rod 25 both connecting the clamps and providing pivots for the arms so that the arms and pressing means can be swung in reference to the page, and springs connected at their ends to the respective clamps and arms to hold the pressing means against the paper under tension.

HARRY VAN BUREN.
